LAWSON CLARK AND GEORGE G. JEFFERY, OF BARNESVILLE, OHIO.

WIRE-STRETCHER.

1,120,790.

Specification of Letters Patent. Patented Dec. 15, 1914.

Application filed February 24, 1914. Serial No. 820,481.

To all whom it may concern:

Be it known that we, LAWSON CLARK and GEORGE G. JEFFERY, citizens of the United States of America, and residents of Barnesville, county of Belmont, and State of Ohio, have invented certain new and useful Improvements in Wire-Stretchers, of which the following is a specification.

This invention relates broadly to improvements in wire stretchers, and specifically to a device which is particularly adapted for stretching one or a plurality of fence wires.

The primary object of the invention is to provide a simple, durable and conveniently operated stretcher for the wires of wire fences.

A further object is to provide a stretcher frame designed for mounting in a stationary position and adapted to be operated by one man.

A still further object is to provide a wire-stretcher of the jack-screw type having means whereby the jack-screw thereof may be quickly removed from and replaced in its mounting in retracted, or initial stretching, position without the tedious operation of reversely screwing it to said position.

With these and other objects in view, the invention resides in the features of construction, arrangement of parts and combinations of elements which will hereinafter be fully described, reference being had to the accompanying drawings, forming a part of this specification, in which—

Figure 1 is a side elevation of the invention, showing the same as it appears in initial stretching position; Fig. 2 is a similar view, showing the wires stretched to the limit of the draw of the jack screw and the means for holding said wires taut while the jack-screw is being returned to initial position; Fig. 3 is a section on the line 3—3, Fig. 1; Fig. 4 is a section on the line 4—4, Fig. 1; Fig. 5 is a top plan view, enlarged, of the jack-screw mounting; and Fig. 6 is a face view of the same.

Referring to said drawings, in which like designating characters distinguish like parts throughout the several views—1 indicates a frame composed of any suitable material and embodying a pair of parallel upright bars 2 disposed at a distance apart to form an intervening opening 3 of suitable dimensions. Rigidly mounted upon one face of said frame is a pair of horizontally disposed arms 4 which are designed to have their

outer ends seated against a post, as 5, in the line of the fence. For mounting the frame 1 with its arms against a post, suitable clamps are provided, said clamps consisting of horizontal rods 6 each of which has a threaded end slidably mounted in a laterally directed arm or lug 7 provided on said frame and has its opposite end shaped to form a hook 8 adapted for engaging the post on the side 65 opposite that engaged by the arms 4. Cranks 9 threaded upon the threaded ends of said rods 6 against the outer faces of said lugs 7 are employed for adjusting said rods for causing the hooks to engage and disengage the post.

Adjustably disposed in a mounting or head-piece 10 carried by the frame 1 is a jack-screw 11 which substantially aligns with the wires 12 to be stretched. The inner end of said jack-screw carries a swiveled ring 13 to which is attached one or more chains 14 which are adapted for connection to hooks or rings 15 carried by a suitable clamp 16 which rigidly grips the wire or 80 wires 12 to be stretched. A crank 17 fixed upon the outer end of said jack-screw affords means whereby power may be applied for rotating the latter to effect the stretching of the wire or wires.

When the jack-screw has been rotated to the limit of its forward movement, as shown in dotted lines in Fig. 1 and in full lines in Fig. 2, a cable or chain 18 is attached to, or is looped around the clamp 16 and, being 90 drawn up tight, has its ends detachably connected to a hook or hooks 19 carried by the frame, as is shown in Fig. 2, said cable or chain serving to prevent retraction of the fence wires when the jack-screw is relieved of tension, as when the latter is returned to its initial position for continuing the stretching operation.

In order that the jack-screw may occupy a position wherein the draft chain or chains 14 will not engage the post 5, the arms 4 preferably have a slight lateral inclination, as is most clearly illustrated in Fig. 4.

The head-piece or mounting, which is designated generally by the numeral 10, is of a special novel form designed to admit of quick adjustment of said jack-screw from one position to another when not under tension. It comprises two complementary body sections 20 and 21, the former having oppositely disposed trunnions 22 at its opposite ends. Said head-piece is adapted to occupy

a position in the opening 3 between the upright members 2 of the frame, with its trunnions 22 removably mounted in suitable seats, as recesses or notches 23, provided in 5 said upright members. A plurality of such seats 23 is preferably provided, the same being arranged in pairs, thus affording means which permit of the vertical adjustment of said head-piece to a most convenient 10 or desirable position.

The section 20 is of substantially V-shape in face elevation, and has one-half of the threaded bore 24 for the reception of the jack-screw located at the angle of the V. 15 The section 21 is complementary to said section 20, being adapted to fit closely on the V-shaped face of the latter, to form a body of rectangular shape, and has the other half of said bore complementally located. Said 20 sections are pivotally connected, or hinged, adjacent one end of the body, the section 20 having an upright lug 25 received in a corresponding recess 26 in the section 21, and a pivot pin 27 being directed through said lug 25 and the portions of said section 21 located at opposite sides of said recess 26. A vertical pin 28 having a winged head 29 has its lower body portion rotatably mounted in the section 20 adjacent to one end and has 30 its upper body portion received in a recess 30 provided in the corresponding end of the section 21. When said pin 28 occupies a position wherein the wings of its head extend in a direction longitudinal with respect to the body of the head-piece, the section 21 may be freely raised and lowered without hindrance, permitting the ready removal or insertion of the jack-screw. But, 35 as is obvious, when said pin is turned so that 40 its wings overlie the portions of said sec-

tion 21 located at opposite sides of the recess 30, said sections are firmly interlocked upon the interposed jack-screw.

From the foregoing it will be seen that the invention is extremely simple in its 45 construction, that it may be easily operated by one man without the necessity for an attendant, and that it may be made strong and durable, there being few, if any, parts which are likely to become out of order. It 50 will furthermore be seen that the device is adapted for use for stretching wires on either side of the fence posts, a mere reversal of the position of the frame 1 being the only requirement to shift the stretching to 55 the opposite side of the post from that illustrated in Figs. 1 to 4, inclusive, of the drawings.

What is claimed is—

A wire stretcher comprising a pair of upright parallel frame members, means for mounting said frame members upon a fence-post, a head-piece disposed between said frame members, a jack-screw mounted in said head-piece, and means for attaching fence wires to said jack-screw, said head-piece comprising a pair of complementary sections having hinged connection one with the other, one of said sections having trunnions seated on said frame members, and means carried by said sections whereby they are rigidly interlocked upon the jack-screw.

In testimony whereof we affix our signatures in presence of two witnesses.

LAWSON CLARK.
GEORGE G. JEFFERY.
